United States Patent

Des. 240,637
Patented July 20, 1976

240,637

SPEAKER CABINET

Robert A. O'Neil, Glen Ellyn, Ill., assignor to The Seeburg Corporation of Delaware, Chicago, Ill.

Filed Aug. 21, 1974, Ser. No. 499,166

Term of patent 14 years

Int. Cl. D14—01

U.S. Cl. D26—14 G

FIG. 1 is a left front perspective view of a speaker cabinet showing my new design;

FIG. 2 is a front elevation view thereof;

FIG. 3 is a left side elevation view, the right side view being a mirror image thereof;

FIG. 4 is a bottom plan view thereof;

FIG. 5 is a rear elevational view thereof; and

FIG. 6 is a top plan view thereof.

I claim:

The ornamental design for a speaker cabinet, substantially as shown and described.
